UNITED STATES PATENT OFFICE.

FRANK O. BRYAN, OF UTICA, NEW YORK, ASSIGNEE OF ONE-HALF TO EDWARD F. WETZEL, OF UTICA, NEW YORK.

GARMENT.

1,145,467.

Specification of Letters Patent. Patented July 6, 1915.

Application filed June 27, 1914. Serial No. 847,628.

To all whom it may concern:

Be it known that I, FRANK O. BRYAN, a citizen of the United States, residing in the city of Utica, county of Oneida, and State of New York, have invented certain new and useful Improvements in Garments; and I do hereby declare the following to be a full, clear, and exact description of the invention, such as will enable others skilled in the art to which it appertains to make and use the same.

This invention is directed to the provision of an improved form of union undergarments, particularly garments of the type known as closed-crotch garments.

The object of the invention is to provide an improved form of garment of this character, preferably of knitted material, which conforms more perfectly to the figure of the wearer, which permits of greater freedom of movement, which has a comfortable closure of a single thickness of material at the crotch and which may be readily manufactured at relatively small cost.

One of the features of the invention resides in the provision of an improved form of crotch-piece extending from the front to the rear of the garment and secured by suitable sewing to the portions forming the front and back of the garment. The crotch-piece is preferably formed from a piece of knit fabric and one of its distinguishing characteristics is that it is bifurcated lengthwise from its rear edge to a point adjacent to its front edge, thus forming two portions on opposite sides of the bifurcation which are laid one over the other when securing the crotch-piece to the back of the garment. In this way, the crotch is closed by a single thickness of material and a flap opening is provided in the back of the garment in a simple and economical form in such a manner that proper shaping of the garment may be readily attained and fastening and unfastening of this opening may be readily effected. Another feature of this form of crotch-piece resides in the shape which is given it whereby, when the piece is secured in proper relation to the front and back of the garment, the latter will have the form which is desirable in order that it will properly fit the wearer. For this purpose, the crotch-piece has the front edge thereof substantially at right angles to its lateral edges. This front edge of the piece

is secured to the part forming the front of the garment and then the lateral edges of the piece are secured to the back of the garment along the edges of the lengthwise opening provided therein. This shape of the crotch-piece and securing the piece to the garment in this manner provide the necessary fullness about the crotch-piece which conduces to a proper fit of the garment.

Another of the features of the invention involves the provision of inserts of a special form at the shoulders of the garment so arranged as to provide for elasticity over the shoulders, the provision of such elasticity being specially desirable in garments of the closed-crotch type. In accordance with the invention, two inserts are provided at the shoulders of the garment each extending from the neck opening to the arm-hole, these inserts being of knit fabric and having the ribs thereof extending substantially transverse to the ribs of the material of the front and back of the garment. Each of the two inserts is of triangular form, has two of its edges sewed to the front and back of the garment and has the third edge sewed to a sleeve secured in the arm-hole of the garment, the apex of this triangular insert opposite the side which is secured to the sleeve being at or close to the neck opening of the garment, it being preferably sewed to a neck-band extending around the neck opening. The material of these triangular inserts will stretch readily in the direction of the length of the ribs of the material forming the front and back of the garment so that they supply the elasticity which is desirable over the shoulders of the wearer, such elasticity being particularly desirable in a garment of the closed-crotch type in order that the garment will not bind when the wearer leans over. This special form of insert is also highly advantageous in that it assists materially in holding the sleeve in position and in that it relieves any drawing from the underside of the sleeve.

These and other features of the invention will be better understood by reference to the following description taken in connection with the accompanying drawings which show the preferred embodiment of the invention.

In these drawings, Figure 1 is a front view of the garment; Fig. 2 is a back view; Fig. 3 is a view of the crotch-piece and

22
Fig. 4 is a horizontal sectional view looking upward, showing the crotch-piece in plan view.

Referring to these drawings, the garment shown in Figs. 1 and 2 is a union undergarment made of knit fabric. As is indicated in Figs. 1 and 2, the ribs of the fabric forming the front 5 and back 6 of the garment extend vertically so that in the vertical direction, the fabric is relatively inelastic while in the transverse direction, the requisite degree of elasticity is provided. The garment is provided with a front opening as shown at 7 and suitable fastening devices 8 therefor. The front opening 7 terminates at the neck opening 9 having a neckband 12. Short sleeves are shown at 10, these being secured to the front and back of the garment by suitable sewing. As will be seen, the garment is of the closed-crotch type and provision is therefore made for supplying elasticity over the shoulders. For this purpose, triangular inserts 11 are provided, each extending over one of the shoulders, these being made of knit fabric and having the ribs thereof extending in a direction transverse to the ribs of the front and back of the garment so that these inserts are elastic in the direction in which the front and back of the garment are relatively inelastic. The inserts 11 are of triangular form as is shown in Figs. 1 and 2. Two of the sides of each insert 11 are secured one to the front and the other to the back of the garment by suitable sewing and the third side of the triangular insert is secured to the end of the sleeve 10. The apex of this triangular insert opposite the side which is secured to the sleeve 10 lies adjacent to the neck opening 9, it being preferably secured to the band 12 which extends around the neck opening. These triangular inserts provided upon the shoulders of the garment and so arranged as to be elastic in the direction in which the front and back of the garment are relatively inelastic enable the garment to give over the shoulders as the wearer leans forward. The provision of the degree of elasticity over the shoulders afforded by these triangular inserts which are of substantial width adjacent to the arm-holes is specially desirable in a garment of the closed-crotch type which but for such provision would be apt to bind as the wearer moves. This form of insert is also effective in holding the sleeve in proper position and serves to relieve the drawing from under the arm.

The crotch-piece is shown separated from the garment in Fig. 3. As will be seen from that figure, its front edge 13 is substantially at right angles to its lateral edges 14 and 15. This piece is bifurcated from its rear edge lengthwise to a point 16 adjacent to the front edge 13, thus providing portions

17 and 18 on opposite sides of the bifurcation. The crotch-piece so formed is secured to the front and back of the garment extending from front to rear of the garment in the manner indicated in Figs. 1 and 2. For this purpose, the back has a lengthwise opening therein of a length sufficient to receive the crotch-piece which extends upwardly a substantial distance along the back as indicated in Fig. 2, preferably, to a point above the waist-line. The front edge 13 of the crotch-piece is secured to the front of the garment along line 19 of Fig. 1 and the lateral edges 14 and 15 of the piece are secured to the back of the garment. Prior to securing the crotch-piece to the back of the garment, the two portions 17 and 18 thereof are laid one over the other. The edge 14 of the crotch-piece is then secured to one of the edges of the opening in the back along the line 20 of Fig. 2. The opposite lateral edge 15 of the crotch-piece is secured to the other edge of the opening in the back along the line 21 of Fig. 2. The upper, overlapping ends of the portions 17 and 18 are secured together and to the back 6 of the garment down to the point 22 of Fig. 2. From this point down, the inner edge of the portion 17 is detached from the underlying portion 18 of the crotch-piece except as it may be held by detachable fastening devices which are provided for retaining the portions 17 and 18 in their normal overlapping conditions. These detachable securing devices preferably consist of two buttons 23 which are secured to the underlying flap 18 of the crotch-piece, one at the inner edge of the flap and engaging a corresponding button-hole in the body of the garment or in the flap 17 adjacent the seam line (see Fig. 2) to prevent discomforting wrinkling or doubling over of the flap when in use, and the other in position to be engaged by a button-hole 24 at the outer edge of the overlapping flap 17 to fasten that flap in position.

The construction of the crotch-piece herein shown and described provides means for readily opening and closing the back opening of the garment and the construction is such that the garment may be readily manufactured at relatively low cost. Furthermore, this construction of the crotch-piece and the manner in which it is secured to the front and back of the garment make the latter of such shape that it conforms readily to the figure of the wearer so as to provide the requisite fullness at the desired points and close the crotch without undesirable folds or double thicknesses of material.

What I claim is:

1. A union undergarment having a front, a back having a lengthwise opening therein, a crotch-piece, the front edge of which is substantially at right angles to its side edges, and means securing the front edge of

the said piece to the front of the garment and the side edges thereof to the edges of said lengthwise opening in the back; substantially as described.

- 5 2. A union undergarment having a front, a back having a lengthwise opening therein, a crotch-piece, the front edge of which is substantially at right angles to its side edges, and means securing the front edge of the 10 said piece to the front of the garment and the side edges thereof to the edges of said lengthwise opening in the back, said piece being bifurcated from its rear edge a substantial distance toward its front edge and 15 being secured to the back of the garment with the portions on opposite sides of the bifurcation overlapping each other; substantially as described.
3. A union undergarment consisting of a

shirt and drawers integral with the shirt 20 and of the closed-crotch type, said garment being formed of knit fabric the ribs of which extend vertically and having a neck opening and arm-holes, sleeves secured in the arm-holes and two triangular inserts at 25 the shoulders of the garment each secured along two of its sides to the front and back of the garment and along the third side to a sleeve, said inserts having the ribs thereof extending substantially transverse to the 30 ribs of the front and back of the garment; substantially as described.

In testimony whereof I affix my signature, in presence of two witnesses.

FRANK O. BRYAN.
